UNITED STATES PATENT OFFICE.

PETER O. EGELAND, OF AKELEY, MINNESOTA, ASSIGNOR OF ONE-HALF TO BENJAMIN F. DANIEL, OF AKELEY, MINNESOTA.

CEMENT-MIXER.

1,340,880.

Specification of Letters Patent. Patented May 25, 1920.

Application filed March 29, 1917. Serial No. 158,324.

To all whom it may concern:

Be it known that I, PETER O. EGELAND, a citizen of the United States, residing at Akeley, in the county of Hubbard, State of Minnesota, have invented certain new and useful Improvements in Cement-Mixers; and I do hereby declare the following to be a full, clear, and exact description of the invention, such as will enable others skilled in the art to which it appertains to make and use the same.

This invention relates to cement mixing machines, and has particular reference to those mixers which are employed to mix a batch of concrete or cement and then to discharge the same.

The object of the invention is to produce a batch cement or concrete mixer which, either as a machine of large capacity or one for small work, may be economically built and operated. The operative parts are by my conception, reduced to a minimum, and the machine as a whole is capable of heavy duty without the probability of frequent breakage or disarrangement.

With the above objects in view and such others as may hereinafter appear, my invention will now be fully set forth and described, reference being had to the accompanying drawings.

In the drawings:—

Figure 1 is a side elevation of the device, Fig. 2 is a longitudinal section,

Fig. 3 is a side view showing the device in dumping position, and

Fig. 4 is a rear view partly broken away for the sake of clearness.

Referring more particularly to the drawings, the main frame comprises sills 1 from which rise standards 2 whose upper ends are connected longitudinally by the side bars 3, and transversely below their tops by the cross bars 4. Mounted between the side bars 3, and journaled upon the spindle 5 is a rocking frame which consists of side bars 6 which are joined substantially in the horizontal plane of the bars 3 by cross bars 7 and 8, the latter connecting the front ends of the side bars 6, and the bar 7 being in reality a heavy block which is secured across the tops of the bars 6 and projects therebeyond so that its ends provide stops which rest upon the upper surfaces of the fixed side bars 3. The block or bar 7 has its upper face inclined rearwardly, and has secured thereon the

bearing 9 within which is journaled the stub shaft 10 which projects rearwardly from the bottom of a mixing drum 11. The mixing drum 11 is of any suitable cylindrical type having a closed bottom and an open top, the bottom suitably carrying the above mentioned stub shaft 10. Interiorly, the drum is provided with the radial mixing blades 12 in suitable position and number.

The forward end of the body of the drum is supported upon a pair of idler pulleys or rollers 13 which are journaled upon the forward ends of brackets 14 mounted upon a second inclined block or transverse bar 15 which also extends across but not beyond the side bars of the swinging, or rocking frame. The surfaces of the pulleys 13 should lie in parallel relation to the outer surface of the drum 11 so as to provide a proper bearing therefor.

Mounted upon the rear end of the stub shaft 10 is a bevel gear 16 which meshes with a second bevel gear 17 carried by a shaft 18. The shaft 18 is journaled in bearings on the rear cross bar 4 and a second bearing bar or support 19 secured across the frame 1, and carries the bevel gear 17 at its forward end in position to freely mesh with the bevel gear 16. The rear end of the shaft 18 is provided with a drive pulley 20 and a removable hand crank 21, so that the machine may be driven either by hand or power.

It will be noted from the foregoing that the shaft 18 is journaled in the fixed frame 1, so that when the rocking frame is thrown forward to free the drum of its contents, the bevel gear 16 is carried out of contact with the gear 17, and thereby the drum 11 is stopped from its mixing action as soon as the process of dumping the batch has begun. As the drum is tipped forwardly into the position shown in Fig. 3 the bar 8 at the forward end of the rock frame is thrown against a transverse rest or stop 22, which may be used as a bumper or jar against which the frame may be struck in order to free the drum 11 of all of its contents. The rear end of the rocking frame carries a cross bar 23 which is of a length greater than the width of the main frame and serves as a handle bar for the ready manipulation of the rock frame into and out of its various operative positions. As seen in Figs. 1 and 2 this handle bar overlies the rear cross bar

4 between the rear ends of the side bars 3
and the drive pulley 20, and as it projects
laterally beyond both, it may easily be
grasped and raised when the drum is to be
dumped. Yet its position is such that it
5 would not interfere with a belt if one were
led laterally from the pulley, nor would it
interfere with the manual use of the crank
handle 21.

10 From the foregoing it will be apparent
that I have provided a very simple and com-
plete mixing machine which may be practi-
cally constructed in various sizes, either for
heavy work or for small batch mixing. The
15 parts are very few in number, and are fur-
thermore all of heavy solid character, so
that the device is fully capable of standing
the hard usage to which machines of this
type are usually subjected, without the prob-
20 ability of frequent repair or disarrange-
ment of parts.

What I claim as my invention is:—
In a cement mixer, the combination with

side bars fixed in spaced relation, a fixed
stop below their front ends, and driving
mechanism between their rear ends; of a
25 rocking frame pivoted between said bars and
having front and rear blocks, the ends of
the latter projected and forming stops to
rest on the side bars in one position of said
30 frame, a cross bar at the front end of the
frame to contact with said stop in another
position of such frame, a handle bar fixed
across the rear end of the rocking frame,
35 bearings on said blocks, a drum mounted on
the bearings of one block and having a shaft
mounted in the bearings of the other block,
and a wheel on said shaft adapted to coact
with said driving mechanism in one posi-
40 tion of the frame.

In testimony whereof, I affix my signature
in the presence of two witnesses.

PETER O. EGELAND.
